UNITED STATES PATENT OFFICE.

WESTERN UNDERWOOD, OF LOS ANGELES, CALIFORNIA.

DESIGN FOR A STREET-LIGHT LANTERN.

Application filed March 27, 1928. Serial No. 26,022. Term of patent 7 years.

To all whom it may concern:

Be it known that I, WESTERN UNDERWOOD, a citizen of the United States, residing at Los Angeles, in the county of Los Angeles and State of California, have invented a new, original, and ornamental Design for Street-Light Lanterns, of which the following is a specification, reference being had to the accompanying drawing, forming a part thereof.

Fig. 1 is a side elevation of the street light lantern showing my new design, and Fig. 2 is a bottom end elevation of the street light lantern.

I claim:

The ornamental design for a street light lantern, as shown.

WESTERN UNDERWOOD.
